UNITED STATES PATENT OFFICE.

JOHN M. WALCUTT, OF DOUGLASTON, NEW YORK.

BOX.

1,185,560.

Specification of Letters Patent. Patented May 30, 1916.

Application filed November 12, 1913. Serial No. 800,543.

To all whom it may concern:

Be it known that I, JOHN M. WALCUTT, a citizen of the United States, residing at Douglaston, in the county of Queens and State of New York, have invented certain new and useful Improvements in Boxes, of which the following is a specification, reference being had therein to the accompanying drawing.

10 This invention relates to receptacles and particularly to paper boxes.

The object is to provide a box, preferably formed from a single blank, and one which may conveniently be opened and shut, and 15 which is of simple construction and can be economically manufactured.

Another object within the contemplation of my invention is to construct a box in its entirety from a single blank, preferably, 20 and from which blank is formed a plurality of primary portions, one encompassing the other, so that said portions are adapted to telescope one into the other; there being end-portions also formed from the blank and 25 integral with the primary portions; one of the end-portions constituting a closure therefor and being so constructed as to be actuated by the telescopic movement of the two primary portions to open and close one 30 end of the box.

A further object of the invention is so to cut and mark the blank that the different portions thereof which are to constitute the primary and secondary portions of the box 35 may be conveniently folded and pasted without the exercise of a high degree of skill.

This invention in general seeks to provide a paper receptacle which is particularly adapted for holding small articles, and 40 which structure, from an operative standpoint, will in practical use be characterized by a high degree of simplicity and, at the same time, be easily and conveniently manipulated.

45 Other objects and advantages will in part be obvious from the annexed drawings and will also be in part pointed out in the following description.

The invention resides broadly in the features of construction, the arrangement of the parts thereof, and in the novel aggroupment of the same, all as will be exemplified in the constructions hereinafter set forth,

and the scope of application of which will be indicated in the claims hereto appended. 55

The accompanying drawings appended hereto as a part of this disclosure illustrate some of the possible utilizations of the invention, it being manifest therefrom that other possible utilizations and embodiments—and ones which employ the underlying principles of the invention—fall within the spirit thereof and within the objects contemplated thereby.

In the drawings Figure 1 shows a blank 65 cut and marked to form a box of one embodiment of the invention; Fig. 2 is a view in perspective of the box completely formed and with the end-closure shown in its closed position; Fig. 3 is a view in vertical transverse section of the box showing particularly how the various parts of the blank are folded upon one another and illustrating the end-closure in its open position; Fig. 4 is a view in perspective illustrating graphically 70 the manner of effecting the telescopic movement of the primary portions of the box whereby the end-closure which is integral with said portions is actuated to open and close the box; Fig. 5 shows another blank 75 cut and marked to form a box of another embodiment of my invention; Fig. 6 is a view in perspective of the completed box; Fig. 7 is a view in vertical transverse section thereof showing the end-closure in its 80 closed position, the same as in Fig. 6; Fig. 8 is also a view in perspective showing the manner of manipulating the telescoping portions of the box to actuate the end-closure; Fig. 9 shows still another blank cut and 85 marked to form a box of a third embodiment of my invention; Fig. 10 is a view in perspective of the completed box of this third embodiment; Fig. 11 is a view in vertical transverse section thereof showing the 90 end-closure—the same as in Fig. 10—in its closed position; and Fig. 12 is a view also in perspective illustrating the manner of manipulating the various parts to operate the end-closure of the structure. 100

In the several embodiments of my invention, it is to be understood that there will be a plurality of portions, primary and secondary; most if not all of which will be formed from a single blank. Any suitable 105 material may be used in constructing the

box as, for example, cardboard, paper, leather, wood, metal, and the like; the desideratum being that such materials shall preferably be flexible so that the several parts may be made from the single blank and bent or folded when forming a structure. Essentially, the box includes a plurality of primary portions cut and folded so that each will have four sides, one portion being adapted to telescope into the other; there being an end-closure portion integral with both of the primary portions and preferably comprising two sections of substantially the same relative dimensions and adapted to be actuated to open and close the box by the telescopic movement of said primary portions.

Referring to the embodiment revealed in Figs. 1 to 4 inclusive, the reference-character A designates, generally, a blank cut and marked, as shown, to form one primary portion 1, a second primary portion 2, and secondary portions including an end-closure 3 formed between the primary portions, and end-flaps 4 formed at the side of the primary portion 2.

The dotted lines in Fig. 1 indicate the lines at which the material is to be folded to form the sides and ends of the box. In this instance, the sections of the primary portion 2 will be folded at said lines to form a four-sided structure so that the sections of the primary portion 1 may be folded around the same, also to form a four-sided structure to encompass it. The said primary portion 2 is adapted to have a telescopic or sliding movement within the primary portion 1. The secondary sections forming the end-closure 3 will then occupy such a position that they will be united to the proximate ends of the slidable primary portions 1 and 2, so that when said portion 3 occupies its open position, illustrated in Figs. 3 and 4, the two sections 3^a, 3^b of said closure portion 3 will be spaced and be positioned outside of the two four-sided structures; but, when actuated—by the telescopic or sliding movement of the two primary portions 1 and 2—said sections 3^a will be folded over and into the open end of the primary portion 1 and effect a closure of one end of the same. Preferably and as shown, these sections 3^a are of corresponding dimensions. The primary portions, on the other hand, are in this instance of relatively different dimensions in order to provide convenient means for the user to grasp the respective portions and manipulate one relatively to the other to fold the portion 3 into the open end of the box, as shown in Fig. 2. The other secondary portion 4 includes two flaps 4^a, 4^b and a two-part flap 4^c and 4^d. The flaps 4^a are folded so that their ends will overlap somewhat, whereupon the flap 4^b, 4^c is folded around over the same and insert-

ed into the inside of the primary portion 2, as shown in Fig. 3.

In the modification illustrated in Figs. 5 to 8 inclusive, the general features of the embodiment already described are retained; but in this instance the blank B is somewhat differently cut and marked whereby one of the primary portions 5 is so constructed as to include extended side sections 5^a and end-sections 5^b, the latter being pasted one upon the other, as shown in Fig. 6. In this instance, also, the closure-portion 6 includes three sections 6^a, 6^b and 6^c; the sections 6^a and 6^c being of relatively large area, while the section 6^b is of small area. These three sections combine to form an end-closure whereby the section 6^c will be outermost and constitute one end of the box, the section 6^b will occupy a position parallel to the side walls of the box, while the section 6^a will occupy a position at an angle to the section 6^c—all as shown clearly in Fig. 7. The other secondary portion 7 is substantially the same in form and arrangement as already described in connection with the first embodiment, and includes flaps 7^a, 7^b and 7^c, 7^d. In this second embodiment, the sections 5^a of the primary portion 5, combining with the sections 5^b, constitute a means for limiting the telescopic movement of the primary portions 5 and 8 in one direction. Normally, when the box is closed, as in Figs. 6 and 7, the sections 5^b will lie against the secondary portion 7; but when the parts are operated, by a sliding movement, to open the end-closure 6, as in Fig. 8, the sections 5^b will be spaced from the secondary section 7.

In the modification illustrated in Figs. 9 to 12 inclusive, the blank C is, as may be seen from Fig. 9, cut and folded quite differently from the described method of cutting and folding of the other two forms of blanks. In this instance, the four-sided primary portions 9 and 10 are approximately of the same dimension; and separate means for effecting their relative movement are provided. To this end the blank includes a tab 10^a adapted to occupy a position in a rectangular slot 9^a in the primary portion 9. The end-closure portion 11, in this instance, is of substantially the same form as the end-closure 3 in the first embodiment above described. The other secondary portion 12, constituting the lower end of the box, is of substantially the same form and arrangement as the secondary portion 4 in said first-mentioned embodiment. In this instance, a supplemental portion 13 may be pasted upon the primary portions 9 and 10 at the sides opposite to the closure-portion 11, and this particular portion is adapted to be positioned into the box and occupy a position therein beneath the end-closure 11, as shown in Fig. 11.

As shown in Fig. 12, when the user pushes upwardly on the tab 10^a this will, being integral with the primary portion 10, slide said portion out of the primary portion 9 and thereby open the end-closure 11 and also force the supplemental portion 13 out of the box.

From the foregoing, it will be perceived that I have succeeded in devising a box 10 which is well adapted to achieve the several objects and ends in view. The structure is exceedingly simple and compact in form, and is well suited as a container for various articles, both large and small.

As many changes can be made in the above construction and many other apparently widely different embodiments of the invention can be made without departing from the spirit thereof, it is intended that 20 all matter contained in the foregoing description and shown in the accompanying drawings shall be interpreted as illustrative and not in any limiting sense. It is, therefore, to be understood that the language used in the following claims is intended to cover all of the generic and specific features of the invention which, as a matter of language, might be said to fall therebetween.

30 What I claim is:

1. A box including a plurality of integral portions telescoping one within the other and of relatively different dimensions, and an end-closure portion integral with 35 said portions and comprising sections hingedly connected together and hingedly connected to the telescoping portions, both sections being adapted to be actuated together in angular relation by the telescopic movement of one portion with relation to the other to open one end of the box.

2. A box including two integral portions telescoping one within the other and of relatively different dimensions, and an end-closure-portion integral with the telescoping portions and comprising two sections hingedly connected together and hingedly attached to said portions and adapted to be actuated to open or close the box by the 45 telescopic movement of one portion with relation to the other.

3. A box including two integral portions telescoping one within the other and of relatively different dimensions, and an end-closure-portion comprising two sections of substantially the same relative dimensions and one foldable upon the other and integral with both of said portions and adapted to be actuated to open or close the box by the 55 telescopic movement of one portion with relation to the other.

4. A box including a plurality of portions formed from a single blank and integral one with another, one of said portions telescoping within another thereof, and another of

said portions which is integral with and hingedly connected to the other portions being actuatable to close the box by a telescopic movement of the two telescoping portions.

70

5. A box including a plurality of portions formed from a single blank and integral one with another, one of said portions telescoping within another thereof, said telescoping portions being of relatively different longitudinal dimensions so that one has its ends extending beyond the ends of the other portion, and another of said portions which is integral with and hingedly connected to the other portions being actuatable to close the 75 box by a telescopic movement of the two telescoping portions.

80

6. A box including a plurality of portions formed from a single blank and integral one with another, one of said portions telescoping within another thereof, and another of said portions which is integral with the other portions being actuatable to close the box by a telescopic movement of the two telescoping portions, said box-closing portion being integral with the telescoping portions and comprising a plurality of sections of relatively the same dimensions and one foldable back upon another.

85

7. A box including two integral portions 95 one encompassing the other whereby the portions may have a telescopic movement one within the other, and an end-closure-portion integral with and hingedly connected to ends of both of said telescoping portions and movable to open or close the end of the box by the telescopic movement of said two portions.

90

8. A box including two integral portions one encompassing the other whereby the portions may have a telescopic movement one within the other, and an end-closure-portion integral with ends of both of said telescoping portions and movable to open and close the end of the box by the telescopic movement of said two portions, said closure-portion comprising two united relatively movable sections of substantially corresponding dimensions.

105

9. A paper box comprising two telescoping primary portions, each integral with the other and including a plurality of side-sections, said primary portions being of relatively different longitudinal dimensions whereby each portion may be grasped independently, and an end-closure-portion integral with and hingedly connected to the proximate ends of each of said telescoping portions and movable to open and close an end of the box alternately by the telescopic 110 movement of said primary portions.

115

10. A paper box comprising telescoping primary portions, each integral with the other and including side-sections and being of relatively different dimensions whereby 120 125 130

- each portion may be grasped independently, and an end-closure-portion comprising a pair of correspondingly formed and dimensioned sections adapted to fold against each other and integral with the proximate ends of each of said telescoping portions and movable to open and close an end of the box alternately by the telescopic movement of said primary portions.
- 10 11. A paper box comprising telescoping primary portions, one integral with the other and each including side-sections, an end-closure-portion integral with and hingedly connected to the proximate ends 15 of said telescoping portions and movable to open and close an end of the box alternately by the telescopic movement of the primary portions, said closure-portion including two sections hingedly connected together and 20 movable to occupy an angular relation one with the other, and an end-flap for closing the end of the box opposite said end-closure-portion.

12. A paper box comprising telescoping primary portions, each integral with the other and including four side-sections and being of relatively different dimensions whereby each portion may be grasped inde-

pendently, an end-closure-portion integral with the proximate ends of each of said telescoping portions and movable to open and close an end of the box alternately by the telescopic movement of said primary portions, and a plurality of end-flaps for closing the end of the box opposite said end-closure-portion.

13. A paper box comprising two telescoping primary portions, each integral with the other and including side-sections and being of relatively different dimensions whereby each portion may be grasped independently; and an end-closure-portion comprising a pair of correspondingly formed and dimensioned sections adapted to fold against each other and integral with the proximate ends of each of said telescoping portions and movable to open and close an end of the box alternately by the telescopic movement of said primary portions and including a primary flap and two secondary flaps.

In testimony whereof I affix my signature in presence of two witnesses.

JOHN M. WALCUTT.
